(57) **CLAIM**

The design for a candy bar, substantially as shown and described.

DESCRIPTION

FIG. 1 is a top perspective view of a candy bar showing our new design;

FIG. 2 is a top plan view thereof;

FIG. 3 is a front elevational view thereof;

FIG. 4 is a rear elevational view thereof; and,

FIG. 5 is a right side elevational view, the left side being identical thereof.

The bottom of the candy bar forms no part of the claimed design.
